UNITED STATES PATENT OFFICE.

JOHN W. BATE, OF RACINE, WISCONSIN.

COMBINED GOVERNOR, PUMP, AND THERMAL CONTROL.

Application filed September 11, 1922. Serial No. 587,467.

This invention relates to a combined governor, pump and thermal control and is fully described in the following specification and shown in the accompanying drawings in 5 which—

Figure 1 is a partial side elevation of an engine embodying my invention;

Figure 2 is a view on the line 2—2 of Fig. 1; and 10

Figure 3 is an enlarged partial section on the line 3—3 of Fig. 2.

The invention as illustrated is shown in connection with a well known type of tractor engine having a cylinder bloc 10 secured 15 to a crank-case 11, and a radiator 12 connected at the bottom to the water-jacket of the cylinder bloc 10 by means of the pipe 13 and at the top by means of the reservoir 14 and elbow 15. This arrangement permits 20 of a flow upward through the elbow 15 of the hot water from the cylinders 10, across through the reservoir 14, down through the radiator 12 where it is cooled and back through the pipe 13. This is the well known 25 thermo-siphon system of cooling.

This engine has the usual crank-shaft 16 upon which is keyed a pulley 17 which drives the fan pulley 18 by means of a belt 19.

30 To these well known parts I have added the centrifugal pump 20 which is driven by means of a pulley 21 which bears against the side of the belt 19. The intake 22 of this pump connects with the bottom of the pipe 13 through the T 23. The pump discharges through the pipe 24 and the fitting 25 which is rotatably mounted between the pipe 24 and the side wall 10^a of the bloc 10. This fitting terminates in a nozzle 26 which

40 discharges into the passage 27 forming part of the water-jacket of the cylinder bloc 10.

The pipe 24 is rigidly held by means of the bolts 28 and the endwise pressure on the fitting 25 is maintained by means of the nut 29 threaded thereon which serves to compress the packing 30 and 31 at the two ends.

It will readily be understood that with the fitting 25 in the position shown in Fig. 3 the stream of water directed upward in 50 the direction of the elbow 15 will materially assist the flow of water due to the thermo-siphon action, thereby causing a more rapid flow of water through the radiator 12 with the second cooling of the engine.

55 With the fitting 25 turned to a position 180° from that shown in Fig. 3, by means of

the operating handle 32, the nozzle 26 will point down and will retard the flow of water which naturally tends to flow up and out the elbow 15 due to the thermo-siphon 60 action. The result of this is that the jacket water flows more slowly out the elbow 15 and down through the radiator, thereby maintaining the jacket water and the cylinders at a higher temperature than would 65 normally be the case where the thermo-siphon alone is depended upon to control the rate of flow.

The pipe 24 supports the housing 33 which carries a thin flexible diaphragm 34 of any 70 suitable character, to the center of which a pin 35 is secured. This pin extends out through the side of the housing 33 and is pivotally connected by means of a pin 36 with an operating lever 37 which in turn 75 is hinged connected at 38^a. The lever 37 is connected by means of the links 38 and 39 and the lever 40 to the throttle lever 41 which is connected to the throttle 42 in the fuel-mixture-intake passage 43.

The throttle 42 is normally held open by means of the spring 44. When, however, the speed of the engine exceeds a predetermined rate, the pressure of the water within the pipe 24 on the diaphragm 34 causes 80 the diaphragm to move outwardly and acting through the system of leakages moves the throttle 42 toward closed position against the action of the spring 44. If the speed of the action further increases, the throttle 85 42 is closed still more until finally a point is reached where the throttle will not permit the engine to run any faster for the given load which it is then carrying.

With an increase of load at this time the 90 engine will begin to slow down due to the action of the throttle. As it does so the speed of the pump will accordingly decrease, giving a decreased pressure upon the diaphragm 34 with the result that it will 100 be moved toward normal position under the action of the spring 44 thereby again opening the throttle 42 and permitting the engine to pick up under the increased load until it has again assumed substantially its predetermined speed.

While I have shown and described but a single embodiment of my invention, it is to be understood that it is capable of many modifications. Changes, therefore, in the 110 construction and arrangement may be made which do not depart from the spirit and

scope of the invention as disclosed in the accompanying claims in which it is my intention to cover all novelty inherent in the invention as broadly as possible in view of the prior art.

What I claim as new, and desire to secure by Letters Patent, is:

1. In combination, an internal combustion engine having a water-jacketed cylinder, a thermo-siphon cooling device operably connected thereto, a pump driven by said engine for controlling the circulation of the water through said water-jacket, the discharge pipe from said pump delivering into the side of said water-jacket, and means for controlling the direction of discharge from said pipe to control the thermo-siphon action of the system.
2. In combination, an internal combustion engine having a water-jacketed cylinder, a thermo-siphon cooling device operably connected thereto, a pump driven by said engine for controlling the circulation of the water through said water-jacket, the discharge pipe from said pump terminating in a nozzle delivering at an angle into said water-jacket, and means for rotating said pipe to cause the flow of water from said nozzle to assist or retard the thermo-siphon action.

connected thereto, a pump driven by said engine for controlling the circulation of the water through said cooling device and water-jacket, the discharge pipe from said pump delivering into said water-jacket, and means for directing the discharge from said pipe to control the thermo-siphon action of the system.

3. In combination, an internal combustion engine having a water-jacketed cylinder, a thermo-siphon cooling device operably connected thereto, a pump driven by said engine for controlling the circulation of the water through said cooling device and water-jacket, the discharge pipe from said pump terminating in a nozzle delivering at an angle into said water-jacket, and means for rotating said pipe to cause the flow of water from said nozzle to assist or retard the thermo-siphon action.

JOHN W. BATE.
